UNITED STATES PATENT OFFICE.

DONALD B. ABBOTT, OF YARMOUTH, MAINE.

MOCCASIN.

Substitute for application Serial No. 686,286, filed January 15, 1924. This application filed June 17, 1925.
Serial No. 37,873.

To all whom it may concern:

Be it known that I, DONALD B. ABBOTT, a citizen of the United States, and a resident in the village of Yarmouth, Cumberland County, and State of Maine, doing business at said Yarmouth, have invented certain new and useful Improvements in Moccasins, of which the following is a specification, reference being had to the accompanying drawings. Certain matter herein disclosed is claimed specifically in my copending application No. 37,874, filed June 17, 1925.

It is the purpose of this invention to supplement the invention for which I have obtained Patent No. 1,484,285, Feb. 19, 1924, and to add to that invention additional improvements, the effects of which are that the fit and appearance of the moccasin and especially the bandage-like support under the arch of the foot of the wearer, may be better adapted to fit feet having unusual proportions or unusual anatomical formation, thus making it possible for the manufacturer to construct foot-wear of this class in such manner as will be best adapted to all purchasers.

Reference is here made to my said earlier patent for a detailed description of the construction and method of operation of my improved moccasin foot-wear. Therefore, it will be unnecessary to do more than to state in this application the following controlling features.

To those familiar with the manufacture of true moccasins it is well known that their construction requires the stock, after being cut and partially stitched, to be pulled longitudinally along the bottom of the last over which they are formed, and upwardly at the sides and toe instead of over the top of the last and then downwardly as in the construction of ordinary shoes. This necessary procedure in the construction of the true moccasin causes the material of which they are made, i. e., the rear portion of the vamp, to span the cavity on the underside of the last at the instep section, in other words, at the arch of the foot of the wearer, and makes it practically impossible to so cut and sew the parts together, that the material will hug into the instep cavity notwithstanding the longitudinal and upward strains to which the material is subjected during the socalled lasting operations.

In my former patent above referred to I

fully describe how that part of the moccasin which is called the vamp may be cut under the foot and at its rear portion, so that when suitably stitched it assumes and must assume the desired contour resulting in a snug fit, or as I call it, a bandage-like effect around the instep. It is my purpose in this present application to secure further patent protection for certain modifications in the method of cutting and stitching the moccasin vamp underneath the foot, which my somewhat extensive manufacture under my said former construction has developed, whereby, as stated heretofore, superior fit, comfort and appearance may be secured where the conditions are abnormal or at least unusual. I now describe these modifications as follows.

Referring to the drawings, the several figures thereof are arranged in pairs. That is to say, Figure 1 illustrates a plan view shown flat of the vamp of a moccasin having portions cut from its underside and rear portions of the shape shown, and Figure 2 illustrates a plan view of the vamp of Figure 1 after the edges of the openings have been brought together and stitched. Similarly Figures 3 and 4 constitute another pair of figures showing a different method of removing portions from the underneath rear part of the vamp; and the same is true of Figures 5 and 6, 7 and 8, 9 and 10.

Describing now the pairs of figures above referred to: in Figure 1 it will be noted that there are what may be called two main openings in the rear portions of the vamp. The opening (1) is much larger than the opening (2) which, however, connects with opening (1). This feature is common to all of the figures. It will be noted that the edges of both openings Nos. 1 and 2 in Figure 1 are curved, and that the length of the side (3) and the two sides (4) and (5) of opening No. 2, when brought together will be equal; also that the edges (6) and (7) of the opening No. 1 when brought together will be of equal length, so that when these edges are all brought together and stitched as shown in Figure 2, they will result in two tight seams (8) below and (9) above. The result of cutting the vamp leather in this peculiar curvilinear fashion is to effect a substantial difference in the hugging effect of the bandage-like arch support, for it will be noted that owing to the

curvilinear form of the edges of the two openings the degree of inward pulling of the stock of the vamp will differ in different portions of the resulting seams (8) and (9).
5 Although it may appear immaterial to one not familiar with such matters, whether the edges of the openings—and the resulting seams (8) and (9)—be straight or curved, nevertheless it is a fact that in many cases
10 where straight seams will not produce the desired fit, curved seams will so do—and vice versa.

Referring now to Figures 3 and 4, here there is a different form shown. The two main openings (1) and (2) with their curvilinear edges are shown the same as heretofore but the curvature is differentiated, so that when they are brought together and stitched, they form seams (10) and (11) seen in Figure 4, whereby, a still different bandage-like effect is produced.

In Figures 5 and 6 the same two openings (1) and (2) appear, but in this case there is no projection of the upper opening (2) to the left beyond the confines, in other words, the left-hand edge of opening 1, so that the resulting seams when the edges are brought together and stitched, shown at (12) and (13) in Fig. 6, represent roughly an L-shaped line instead of roughly a T-shaped line as in Figures 1, 2, 3 and 4.

In Figures 7 and 8, the two openings (1) and (2) are again illustrated and when the edges thereof are brought together and stitched they result in another L-shaped seam (14) and (16) as seen in Figure 8. This construction again effects slight modifications in the bandage-like effect present in the finished moccasin.

40 In Figures 9 and 10 the same thing is repeated except that in this construction the edges of the openings (1) and (2) are not curvilinear but straight. But they differ materially from that set forth in my former patent in that no part of the upper opening No. 2 projects to the left beyond the vertical edge of the lower opening No. 1, thus producing an L-shaped seam (16) and (17) instead of a T-shaped seam as shown in said

50 earlier patent.

As stated above, it is the purpose of this invention to show those who practice this art how they can improve the fit, appearance,

and comfort of their foot-wear by modifying the form of the openings set forth in 55 the patent allowed to me as aforesaid, thus carrying that invention beyond anything disclosed in my said former patent and constituting an additional forward step in this art, said earlier invention having been received by the public as has been demonstrated by my recent manufacture and sale of moccasins embodying my inventions as a valuable and important forward step in the construction of foot-wear of the moccasin 60 class.

This application is a substitute for my abandoned application Serial No. 686,286, filed Jan. 15, 1924.

I claim as my invention:

1. A moccasin, the vamp portion of which on its under side has a curved seam extending longitudinally of the vamp from its rear edge toward the ball portion of the vamp and another curved seam in front of 75 that first mentioned which extends crosswise of the vamp.

2. A blank for the vamp portion of a moccasin having an open portion in the rear part of its under side wider at its outer than 80 at its inner end and having adjacent to said first mentioned opening an open portion which is wider at its front than at its rear end, the opposed edges of both openings being curvilinear in outline.

3. A blank for a moccasin vamp having a tapered open portion in the rear part of its under side extending toward the ball portion of the blank and which has curved sides of substantially the same length, said blank 90 having also another open portion, forward of the first mentioned open portion, extending generally crosswise of the blank and having curved sides of substantially the same length.

4. A blank for a moccasin vamp having in the rear part of its under side two openings, one extending in a generally longitudinal direction, and the other in a generally transverse direction, the opposed edges of 100 each opening being curved and of substantially equal length.

In testimony whereof, I have hereunto subscribed my name.

DONALD B. ABBOTT.
